UNITED STATES PATENT OFFICE.

EDMUND O. SCHWEITZER AND ALFRED HERZ, OF CHICAGO, ILLINOIS.

FUSE DEVICE.

1,033,123.

Specification of Letters Patent.

Patented July 23, 1912.

Original application filed April 3, 1907, Serial No. 366,219. Divided and this application filed August 26, 1909. Serial No. 514,719.

To all whom it may concern:

Be it known that we, EDMUND O. SCHWEITZER and ALFRED HERZ, citizens of the United States, residing at Chicago, in the county of Cook and State of Illinois, have invented a certain new and useful Improvement in Fuse Devices, of which the following is a full, clear, concise, and exact description, reference being had to the accompanying drawings, forming a part of this specification.

Our invention relates to fuse devices, and especially to a type of fuse device adapted for use in connection with high tension currents.

This application is a division of our application, Serial No. 366,219, filed April 3, 1907. In said other application we show two types of device involving certain features in common. In the present application we show one of the same devices, claiming specifically certain points or features not found in common in both types of device.

In the accompanying drawings—Figure 1 is a cross-section of a fuse device embodying our invention. Fig. 2 is a horizontal section of the same. Fig. 3 is a cross-section taken on the line 3—3 of Fig. 1.

The device shown comprises a casing 1, conveniently made of insulating material—for example, porcelain—and having a cover 2, desirably made of the same material. The bottom of the casing 1 is provided with an elevated or raised portion 3, which forms a support for two fuse-holding blocks, 4 and 5, also made of insulating material. Pins or posts 6, 6, are secured to the corners of the projection 3, and provided with

adjustable nuts 7, 7, and surrounded by coil springs 8, 8, which act down upon the upper or outermost block, 5. A fuse 9 is interposed between the blocks 4 and 5, the springs 8, 8, compressing the block 5 firmly against the same. The fuse is extended beyond the ends of the blocks 4 and 5, and carried to metallic posts 10, 10, which are mounted in the base of the casing 1, and

have ends or terminals 11, 11, projecting out therefrom for connection.

The cover 2 is provided with a hinged or swinging member 12, carried by a pin or spindle 13, and subject to the tension of a coiled spring 14, tending to swing and hold said member normally against the block 5. The partition 12 thus divides the interior of the casing into two compartments.

In the operation of the device, the fuse 9 is normally in the position shown in the drawings between the blocks 4 and 5. Upon the passage of an overload current, the fuse softens, and the block 5, acting by spring pressure, immediately compresses the fuse, crushing and disseminating the same before it has time to blow. The result is that the fuse is really obliterated or snuffed out, and does not actually blow, as is customary with fuses. Consequently, there are none of the usual accompaniments of fuse action, namely, arcing and vaporization of the fuse material. Thus, the fuse device is capable of use in high tension circuits, where the ordinary fuse cannot be used, the device acting to open the circuit on very high voltages without any arcing or explosion, or other disastrous and dangerous results.

What we claim as our invention is:

1. A device of the class specified comprising a casing having its bottom provided with a projection forming a fuse support, a fuse-block adapted to rest upon a fuse on said projection, terminals in the bottom of the casing on opposite sides of the fuse supporting projection, pins on said projection and extending through the block, and springs on said pins acting against said block.

2. A device of the class specified comprising a casing having a fuse supporting member, terminals for the fuse, a fuse block and springs for the same, and a cover having a spring-actuated member acting upon said fuse block.

3. A device of the class specified comprising a casing having its bottom provided with a projection adapted to support a fuse,

fuse terminals on opposite sides of said projection, a fuse block for the fuse, pins carried on said projection and extending through the fuse block to form guides therefor, 5 springs on said pins acting against said fuse block, and a cover having a swinging member extending through said fuse block and provided with springs arranged to force it against the same.

In witness whereof, we hereunto subscribe to our names this 21st day of August A. D., 1909.

EDMUND O. SCHWEITZER.
ALFRED HERZ.
